ELECTRIC SIGNALING SYSTEM.

1,229,463.

Specification of Letters Patent. Patented June 12, 1917.

Application filed August 10, 1916. Serial No. 114,198.

To all whom it may concern:

Be it known that I, HARVEY HUBBELL, a citizen of the United States, residing at Bridgeport, county of Fairfield, State of Connecticut, have invented an Improvement 5 in Electric Signaling Systems, of which the following is a specification.

This invention relates generally to call systems, with more particular reference to what are known as "flash-light" signal installations, in which normally open electric circuits run from a convenient central station to a number of different local stations, whereby an operative at the central station 10 may close any one of said circuits and thereby transmit a message in the form of a pre-arranged signal visible or audible at each of said local stations. These systems are especially adapted to save time and trouble in 15 large factories, mercantile houses, etc., which comprise a number of different and sometimes widely separated departments, and it is frequently necessary to summon from the main office an official or an employee permanently stationed in one of the departments 20 or happening to be in such department when his presence is desired at the main office.

The principal object of the present invention is the provision of a call system of the character outlined which, with a comparatively simple wiring system, will not only transmit any one of a very large number of differently interpretable signals from a single, compact switch-board, but which by a 30 single operation will transmit the same signal simultaneously to a local station in each department—or variously located throughout the building or the plant. I have further in view the provision of a switch-board and 35 connections which will be "fool-proof"—that is to say, one which can be dependably operated by an unskilled and inexperienced employee; also, the provision of signaling devices at the local stations which are simple, 40 compactly arranged and capable of rendering a comparatively large number of different signals through the instrumentality of a minimum number of signaling instrumentalities; also, the provision of means at 45 the switch-board for instantly indicating whether or not the system is in order and the proper signal being transmitted; and, incidental to the above, the provision of an exceedingly comprehensive signaling system 50 which may be installed at a cost comparatively small enough to permit of its installa-

tion by manufacturers and merchants to whom the cost of the installation of more intricate systems would be prohibitive.

My invention will be more readily understood by reference to the accompanying drawings, forming a part of this specification, in which—

Figure 1 is a front elevation of a preferred form of switch-board adapted for use in connection with a system embodying my invention, illustrating diagrammatically certain local appurtenances thereto, a part of the wiring and three of the preferred forms of local-station signaling devices; 65

Fig. 2 is a rear view, in perspective, of the same, the local-station signaling devices being omitted;

Fig. 3 is a fragmentary diagrammatic view of a practical and convenient method 75 of switch-board wiring, and,

Fig. 4 is a perspective view of one of the local-station signaling devices shown diagrammatically in Fig. 1.

While it will be apparent that my invention is applicable to the transmission of forces adapted to produce auditory as well as visual signals, as a preferred embodiment of my invention I shall proceed to describe a flash-light call system embodying my invention 80 as probably a system which is in all respects most satisfactory and economical. In the drawings, therefore, I have shown a switch-board 23 provided with a plurality of snap switches 10-10. For the purposes of illustration, I have shown these switches arranged in six rows of five switches each, making 30 switches in all, although it is to be understood that the number and arrangement of these switches forms no part of this 85 invention. However, where lamps of different colors are employed, the illumination of one or more of which, steadily or intermittently, constitutes a pre-arranged signal, and "tell-tale" lamps are provided at the 90 switch-board to indicate that the proper signals are being transmitted, it is desirable that the switches be arranged in rows, one row for each color of lamp employed, although the number of switches in each row 95 may be varied to meet individual requirements—that is to say, may be varied to make up a total number of switches corresponding to the total number of different signals any one of which it might become 100 desirable to transmit from time to time.

In a flash-light system such as that shown

- and now being described, each of the local-station signaling devices comprises a board or base (Fig. 4) provided with sockets for a plurality of electric lamps 12, the number 5 of lamps preferably corresponding to the number of horizontal rows of switches in the switch-board, six of such rows being shown in the drawings, whereby for reasons which will subsequently appear each row of 10 switches in the switch-board more particularly appertains to lamps of a certain definite color and a lamp of each of the colors employed may be mounted in said board or base. One of these boards or bases, with 15 the differently colored lamps mounted thereon, is located in each department of the plant or at such other place as any party or parties desired to be summoned are likely to be found.
- 20 A pre-arranged system of signals is of course essential. For instance, a single white lamp, burning steadily, may indicate that the presence of a certain person is desired at the office; a steadily burning red lamp 25 may convey the same information to another person; a still different message may be conveyed by the combination of two lamps of different colors burning steadily; another pre-arranged signal may be the constant glow 30 of a lamp of one color and the intermittent glow or flashing of a lamp of another color. In fact, it will be apparent that a practically unlimited number of variations of the signal 35 is possible, the same signal being simultaneously transmitted to practically any desired number of local stations.
- For the purposes of this description, let it be assumed that the switch 10 in the upper left-hand corner (Fig. 1) of the switch-board controls the circuit which includes the 40 white lamp of the lamps 12 in the boards or bases at each of the local stations. The remaining switches in the same row also control circuits which include each of said white 45 lamps, either separately or in combination with a circuit which includes lamps of a different color, or circuits which, through the deflection of one of the branches thereof through what is known as a "flasher", cause 50 the illumination of the white light intermittently with single flashes at regular intervals, or double or triple flashes at regular intervals, or the alternate flashing of the white lamp and one of the colored lamps.
- 55 Similarly, the switch at the left end of the second row may control the circuit which includes green lamps, and the switches in this row may be correspondingly adapted to transmit signals which comprise a steadily 60 burning green lamp, a flashing green lamp, or a combination of the green lamp and the lamp of another color burning steadily or flashing alternately or intermittently. It will be seen that in this manner a practically 65 unlimited number of different simple

and compound signals may be transmitted to a large number of receiving stations each equipped with a relatively very small number of lamps. In fact, it may be figured out that the number of different signals 70 which may be transmitted to a six-lamp station is for all practical purposes limited only by the number of switches which can be accessibly arranged at the central station and the limit of practicability in the intricacy of the wiring. 75

In connection with the preferred embodiment of my invention herein shown and described, I employ what is termed a flasher. This "flasher" is a common and well-known 80 device of commerce, readily purchasable on the market, and need not be described in detail in this specification. It is well known in this art that the interposition of a flasher in a lighting circuit makes and breaks the 85 circuit at predetermined intervals, causing the flashing on and off of a lamp or the lamps in the circuit, the duration of the flash or the interval between flashes, whether constant or varying, being predeterminable 90 through proper adjustment of the ordinary circuit making and breaking devices within the flasher. In the drawing, I have designated this flasher by the numeral 14 and shown the same having driving connection 95 with an electric motor 13.

The particular method of wiring employed to transmit impulses of a selective character to the local-station signals is of course not of the essence of this invention. 100 Different skilled electricians might naturally wire the switch-board and establish the connections with the local-station lamps in many different ways, each accomplishing the desired purpose and none being without 105 some points of merit. I have illustrated in the drawings, however, a practical, economical, effective and dependable wiring system. In the system shown, the feed wires 15 and 16 of the main circuit are connected in the usual manner with any suitable source of 110 electric energy. A wire 17 leads from the feed wire 15 through an insulating bushing 18 to a terminal 28 within the switch-board. From this terminal 28 lead a plurality of 115 bus-rods 28^a, 28^b, 28^c and 28^d, the number thereof being preferably one less than the 120 number of switches in each of the horizontal rows. From the bus-rod 28^a, a wire 17^a leads through the switch 10^a (Fig. 3) to the bus-bar 29^a, from which leads a wire 24^a passing through one of the fuse-plugs 25 in one of the blocks 26 and thence as one of the wires 24 (Figs. 1 and 2) to the various local stations at each of which it has the usual connection with the socket of one of the lamps—in this case, for purposes of description, preferably the white or clear lamp—the latter being connected in the usual manner with the return wire 16, which is similarly 130

carried through all of the local stations successively. The switch 10^a (again referring to Fig. 3) may be a single-pole switch, as shown, adapted to merely make and break the circuit, and it will be apparent that when the circuit is completed through the switch, the particular lamp 12 among the lamps at each local station in said circuit will burn steadily until the switch is thrown off.

Let it be supposed that another signal is two flashes of the same lamp in rapid succession with an appreciable interval of time between each double flash. To render this signal, of course, the circuit must include the flasher and the latter be provided with the proper making and breaking mechanism. From the wire 17, which leads from the feed wire 15, a branch 19 is directed into the flasher and connected with the parts of the mechanisms thereof which make and break the circuit at intervals which correspond to the desired intervals between the flashes of the signal lamp. From this particular circuit making and breaking mechanism leads the wire 20, which passes through the insulating bushing 18 to connection with the bus-rod 30^a. From this bus-rod 30^a leads the wire 24^b through the switch 10^b through the bus-bar 29^a. A wire 31 leads from the bus-rod 28^a through the switch 10^b to the bus-rod 39^b and thence through the terminal 40 and the wire 41 to the motor 13, from which the wire 32 completes the circuit to the return wire 16. Of course, this switch 10^b must be a double-pole switch which, when closed, establishes two circuits; one, a circuit from the feed wire 15 through the wire 17, the terminal 28, the bus-rod 28^a, the wire 31 which includes the switch 10^b, the bus-rod 39^b, the terminal 40, the wire 41, the motor 13, and the wire 32 to the return wire 16, whereby the motor is energized and the flasher operated; the other a circuit from the feed wire 15 through the wire 17 and the branch 19 thereof, the flasher, the wire 20 therefrom, the bus-rod 30^a, the wire 24^b which includes the switch 10^b, to the bus-bar 29^a, from which a wire leads through one of the fuses to one of the lamps 12 at each local station in the manner hereinbefore described. It will be apparent, therefore, that when these circuits are made through the switch 10^b, the motor will be driven and the mechanism of the flasher thereby set in motion, and simultaneously a current be directed intermittently through the lamp to flash the same at the desired intervals.

Another signal may be the periodically recurring single flash of each lamp appertaining to the switches in this row—for instance, the white or clear lamp to which I have referred. To render this signal the third switch 10^c (Fig. 3) may be employed,

and as the flasher must be included in the lamp circuit a double-pole switch is required. In this case, the motor circuit comprises the wire 17 from the feed wire 15 leading through the terminal 28 to the bus-rod 28^b, from which leads a wire 33 through the switch 10^c to the bus-rod 39^c, and thence through the terminal 40 to the motor 13 which is in circuit with the return wire 16 in the manner described. The lamp circuit 75 includes the wire 17 from the feed wire 15, the branch 19 thereof into the flasher, the wire 21 from the flasher through the terminal 42 to the bus-rod 30^b, and the wire 34 leading through the switch 10^c to the bus-bar 29^b and thence through the lamp in the manner described. In this case, the current from the wire 19 passes through mechanism in the flasher 14 which affects the making and breaking of the circuit at regular intervals, whereby the white or clear lamp at each local station will be flashed at corresponding intervals.

The signal transmitted by the fourth switch in this row may be the alternate flashing of two lamps, one white or clear and one colored. To render this signal, a triple-pole switch must be employed, and a suitable connection established with a bus-bar (corresponding to the bus-bar 29^a) which is common to circuits controlling lamps of a certain color, and as lamps of any one of the various colors are primarily controlled by switches arranged in a horizontal row, for purposes of convenience, wiring is facilitated by providing a bus-bar corresponding to the bus-bar 29^a for each horizontal row of lamps. Assuming that the second row of switches primarily control the circuits which include the green lamps, the fourth switch 95 in the first row (Fig. 1) may be assumed to make circuits which will result in the alternate regular flashing of a clear and a green lamp on the board at each local station. Three circuits, of course, must be established, these three circuits comprising, first, the motor circuit, which includes the wire 17 from the feed wire 15, the terminal 28, the bus-rod 28^c, the wire 35 through the switch 10^d (Fig. 3), the bus-rod 39^d and the terminal 40 to the motor 13, and the wire from said motor to the return wire 16; second, the wire 21 from the flasher, the terminal 42, the bus-rod 30^d, and the wire 36 leading therefrom through the switch 10^d to the bus-bar 100 115 120 29^a and thence through the same (white or clear) lamp in the manner described, whereby said lamp is regularly flashed; third, the wire 22 from the flasher, the terminal 43, the bus-rod 30^e, and the wire 37 leading through the switch 10^e to the bus-bar 29^b, from which a wire 24^b leads through another fuse 25 to another wire 24, the current through which energizes another of the lamps 12 at each of the local stations. Therefore it will be seen 130

that the closing of these three circuits through operation of the switch 10^a will effect the alternate flashing of a white or clear lamp and a lamp of the color associated with the switches in the second horizontal row thereof.

As shown in Fig. 3, the signal designed to be transmitted by operation of the fifth switch in this first row is the same as the signal designed to be transmitted by operation of the fourth switch, except that the alternate flash is by a lamp of a different color. Therefore, the wiring for the circuits controlled by the switch 10^e (Fig. 3) is precisely the same as the wiring described in connection with the switch 10^a except that the wire 38, leading through said switch 10^e, which corresponds to the wire 37 leading through the switch 10^a, connects with one of the bus-bars of the "29" series other than the bars 29^a and 29^b—as, for instance, the bus-bar 29^c, which is common to lamps of a color associated with the switches in the third horizontal row thereof.

From the foregoing, it will be apparent that through the snapping of any one of the switches a pre-arranged and readily distinguishable signal may be transmitted simultaneously to each of a comparatively large number of local stations, and thus any particular officer, employee or other person summoned (or other message conveyed to him) irrespective—within reasonable limits—of his whereabouts in the factory or plant at the time his attendance is desired or other message is required to be conveyed to him. To guard against mistakes in the selection of the proper switch to be thrown, card-holders 11 may be provided, each being adapted to receive a card bearing the name of a particular person to whom it is more or less frequently necessary to convey a message, and each located in immediate proximity to the particular switch the signal controlled by which is intended to be noted and answered by the individual whose name appears upon the identifying card. Of course, the system is adapted to be used in connection with a telephone system, if desired, in which event the signal may convey the message to some particular individual that he is to forthwith communicate with the main office by phone.

It is also highly desirable that the switch-board operator know at all times that the system is working properly, and to this end I provide a series of "tell-tale" lamps, corresponding to the series of lamps at each of the local stations. Of course, this might be done by merely providing an additional local station, with its series of lamps mounted on a single and separate board or base, at or near the central station and in view of the switch-board operator. However, I prefer to arrange these tell-tale lamps 44 on

the switch-board, as shown in Fig. 1, one of said lamps being located at the end of each of the horizontal rows of switches and therefore each of said lamps being of the color of the lamps primarily controlled by the switches in the row at the end of which it is located. If these tell-tale lamps are provided in the form of an additional local station mounted in view of the operator at the switch-board, the lamps will simply be included in the local-station lamp circuits in a manner which will be clearly understood from the foregoing description. If these tell-tale lamps are located at the ends of the horizontal rows of switches on the switch-board, as illustrated in the drawings, branches 24^a may be run from each of the lamp wires 24 (Fig. 3), each leading through one of the lamps 44 from which a common return wire 16^a leads to the main return wire 16. It will thus be seen that in this manner the switch-board operator, upon throwing a switch, is instantly made aware whether or not the signal is being transmitted.

In connection with the present invention, it will be apparent that through the provision of a single and simply operable switch, associated with an identifying card or name-plate, for the transmission of any given predetermined signal, the merest tyro might reasonably safely be depended upon to properly transmit the desired message; that taking into consideration the number of different selective signals which by my new system can be transmitted to many compact local-station receiving devices, the switch-board wiring is of a comparatively simple character; that operation of the system is economical, in that current is never employed except when a signal is being transmitted even when such signal is of an intermittent character and thus necessitates energizing the motor to operate the flasher; and that as a whole the system is simple, effective and dependable, as well as being economical and "fool-proof."

Many modifications of minor details of my improved electric signaling system will doubtless readily suggest themselves to those skilled in the art to which it appertains, and I therefore do not desire to limit myself to the specific construction and arrangement herein shown and described.

I claim as new and desire to secure by Letters Patent:

1. A signaling system of the character described comprising a plurality of electric circuits, a grouped set of electrically actuated signals in said circuits, a grouped series of selective circuit making and breaking devices, an automatic circuit making and breaking device in and common to at least a part of said circuits, and means controlled by each of certain selective circuit making

and breaking devices for inter-connecting and simultaneously energizing a plurality of circuits.

2. A signaling system of the character described comprising a plurality of electric circuits, a grouped set of electrically actuated signals in said circuits, a grouped series of selective circuit making and breaking devices, an automatic circuit making and breaking device including its actuating motor in and common to at least a part of said circuits, and means controlled by each of certain selective circuit making and breaking devices for inter-connecting and simultaneously energizing a plurality of circuits.

3. A signaling system of the character described comprising a plurality of electric circuits, each including at least one signal in each of a plurality of separated and corresponding groups thereof, a grouped series of selective circuit making and breaking devices, an automatic circuit making and breaking device in and common to at least a part of said circuit, and means controlled by each of certain selective circuit making and breaking devices for inter-connecting and simultaneously energizing a plurality of circuits.

4. A signaling system of the character described comprising a plurality of electric circuits, each including at least one signal in each of a plurality of separated and corresponding groups thereof, a grouped series of selective circuit making and breaking devices, an automatic circuit making and breaking device including its actuating motor in and common to at least a part of said circuits, and means controlled by each of certain selective circuit making and breaking devices for inter-connecting and simultaneously energizing a plurality of circuits.

5. A signaling system of the character described comprising a plurality of electric circuits, each of said circuits including at least one signal in each of a plurality of separated and corresponding groups thereof and each of at least a part of the signals in each group being common to a plurality of said circuits, a grouped series of selective circuit making and breaking devices, an automatic circuit making and breaking device in and common to at least a part of said circuits, and means controlled by each of certain selective circuit making and breaking devices for inter-connecting and simultaneously energizing a plurality of circuits.

6. A signaling system of the character described comprising a plurality of electric circuits, each of said circuits including at least one signal in each of a plurality of separated and identical groups thereof and each of at least a part of the signals in each group being common to a plurality of said circuits, a grouped series of selective circuit making and breaking devices, an

automatic circuit making and breaking device including its actuating motor in and common to at least a part of said circuits, and means controlled by each of certain selective circuit making and breaking devices for inter-connecting and simultaneously energizing a plurality of circuits.

7. A signaling system of the character described comprising a plurality of electric circuits, each circuit including a switch and also including at least one lamp in a grouped set thereof, a switch-board upon which said switches are accessibly mounted in regular arrangement, a flasher and its driving motor in and common to at least a part of said circuits, and at least a part of said switches being in and common to a plurality of said circuits.

8. A signaling system of the character described comprising a plurality of electric circuits, each circuit including a switch and also including at least one lamp in each of a plurality of separated and corresponding grouped sets thereof, a switch-board upon which said switches are accessibly mounted in regular arrangement, a flasher and its driving motor in and common to at least a part of said circuits, and at least a part of said switches being in and common to a plurality of said circuits.

9. A signaling system of the character described comprising a plurality of electric circuits, each circuit including a switch and also including at least one lamp in each of a plurality of separated and corresponding grouped sets thereof, a switch-board upon which said switches are accessibly mounted in regular arrangement, one of said grouped sets of lamps being associated with said switch-board, a flasher and its driving motor in and common to at least a part of said circuits, and at least a part of said switches being in and common to a plurality of said circuits.

10. A signaling system of the character described comprising a plurality of sets of differently colored lamps, an electric motor, a flasher, a switch corresponding with each signal to be rendered, and electric connections between the lamps and switches at least a part of which include said motor and said flasher, whereby operation of a switch causes the rendering of a predetermined signal at the several sets of lamps.

11. A signaling system of the character described comprising a plurality of corresponding sets of differently colored lamps, an electric motor, a flasher, a switchboard, a plurality of switches thereon each corresponding with a particular signal to be rendered, and electric connections through the switchboard to the lamps in each set, at least a part of said connections including the flasher, substantially as described, for the purpose specified.

12. A signaling system of the character described comprising a plurality of sets of differently colored lamps, a flasher, a switchboard, a switch thereon corresponding with each signal to be rendered, and an independent electric connection from the switchboard to the lamp of each color respectively in each set of lamps, at least a part of said connections including the flasher, substantially as described, for the purpose specified. 5
13. A signaling system of the character described comprising a plurality of sets of differently colored lamps, a flasher, a switchboard, a switch thereon corresponding with each signal to be rendered, an independent electric connection from each lamp of a particular color in all the sets of lamps to a corresponding switch, at least a part of said connections including the flasher, and means 10 for interconnecting at least a part of said connections, whereby the operation of a switch causes the rendering of a predetermined signal at each set of lamps. 15
14. A signaling system of the character described comprising a plurality of sets of differently colored lamps, a flasher, a switchboard, a switch thereon corresponding with each signal to be rendered, a telltale signal associated with the switchboard, and electric 20

connections through the switchboard to the 30 lamps in each set and to the telltale signal, at least a part of said connections including the flasher, substantially as described, for the purpose specified.

15. A call system of the character described comprising a plurality of sets of differently colored lamps, a flasher, a switchboard, a switch thereon corresponding with each call to be made, a telltale signal on the switchboard corresponding with the lamps 35 in the sets for calls, and electric connections between the lamps, flasher and switches, whereby operation of a switch causes the flasher to produce a predetermined call at the several sets of lamps and a corresponding telltale signal on the switchboard. 40

16. A call system of the character described comprising a plurality of sets of differently colored lamps, a flasher, a switch corresponding with each call to be made, 50 electric connections from each lamp in all the sets of lamps to a corresponding switch, fuses through which said connections pass, and electric connections from the flasher to the switches. 55

In testimony whereof I affix my signature.

HARVEY HUBBELL.
